UNITED STATES PATENT OFFICE

JOHN WICKS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE

TELEPHONE SYSTEM

Application filed September 26, 1925, Serial No. 58,680. Renewed January 27, 1930.

The present invention relates to telephone systems in general, but it is concerned more particularly with telephone systems in which the switches in one office are operated according to a given system of control, while the switches in an adjacent office are operated according to another system of control.

One object of the invention is the production of a novel repeater circuit for use in incoming calls in one office to translate the control arising in the other office so that the local switches may be correctly operated.

Another object is the production of suitable circuit arrangements in the same office whereby the control of the distant switches may be effected without the use of a special repeater in the distant office.

Still another object is the production of suitable circuit arrangements whereby the calling device may be connected by means of a special cord circuit directly to the trunk line to control the distant switches independent of any repeating operation.

Referring now to the accompanying drawings comprising a single sheet, Fig. 1 shows the two-way toll line TL together with certain associated equipment on one end thereof, and Fig. 2 shows the special cord circuit which is used to connect the calling device to the toll lines, there being separate cord circuits (not shown) for making talking connections to and from the toll line.

Before the drawings are described further, the situation which they are especially adapted to meet will be explained a little more in detail. It is assumed that there are two exchanges located sufficiently far from each other that the connections from one to the other are made through the switchboard of the toll operator.

It is assumed as before intimated that the switches in the two different exchanges are operated according to different systems of control. More specifically, the switches in the office in which the equipment shown in the drawings is located are operated according to the well known two-wire system of control, while the switches in the other office are operated according to a modified system of control. According to this modified sys-

tem, the setting of the switches is accomplished over one conductor and a ground return. The other conductor is used to switch the circuits at the exchange into condition to receive the switch operating impulses only while the calling device is off-normal, and is used for supervisory purposes.

It is assumed that it has been found to be most economical to make all the changes in the straight two-wire office permitting the circuits in the other office to remain unchanged.

It usually happens that when an automatic exchange is installed it replaces a manual exchange. The manual toll board however is usually retained practically unchanged owing to the fact that toll connections require the supervision of an operator even after the automatic equipment has been put into operation. Accordingly, it has been found advisable in the present case to leave the cord circuits at the toll board unchanged and to provide a dial cord, Fig. 2, at each position to associate the calling device with the toll line through auxiliary dial jacks, DJ and DJ', Fig. 1.

It will be noted that the line conductor 11 of the toll line TL is normally connected through a jumper on the intermediate distributing frame I. D. F., conductor 28, armature 50 and its resting contact, upper left-hand repeating coil winding, armature 55 and its resting contact, and relay 45 to ground. It will be noted also that conductor 12 of the toll line TL is similarly grounded through a jumper on the I. D. F. conductor 30, armature 51 and its resting contact, lower left-hand repeating coil winding, armature 54 and its resting contact, armature 56 and its resting contact, and relay 47. It may be pointed out further that conductors 11 and 12 are similarly grounded at the distant end.

The detailed description of the operation of the apparatus shown will now be given. For this purpose it will be assumed first that the operator in the distant exchange receives a call intended for an automatic line terminating in the exchange in which the equipment shown in Fig. 1, is located. When the distant operator inserts the plug of her cord 100

circuit into the jack (not shown) on the distant end of the toll line TL, the ground connection is removed from conductor 11 and is replaced by a connection to battery. Conductor 12 however remains connected to ground for the time being. Responsive to the placing of battery on conductor 11, relay 45, which is connected to conductor 11 as above pointed out, energizes and closes at

10 armature 58 a circuit for relay 46, at the same time closing the impulse contacts including armature 59 and its working contact. Relay 46 energizes and at armature 61 places ground on conductor 34, thereby closing a 15 circuit for polarizing winding of the electro-polarized relay 43. The design of relay 43 is such that neither winding alone will bring about its energization. Furthermore, relay 46 at armatures 60 and 62 completes a bridge 20 across the conductors 35 and 36 leading to the associated lineswitch as follows: From the negative conductor 35, through the working contact and armature 60, upper-right-hand repeating coil winding, armature 52 25 and resting contact, upper winding of the electro-polarized relay 43, lower-right-hand repeating coil winding, working contact and armature 62, and the normally closed contacts controlled by armature 64. Responsive 30 to the closure of this bridge, the line switch to which conductors 35 and 36 extend operates to extend the conductors 35 and 36 to a first selector switch in the usual manner.

It will be noted that the impulse branch 35 through armature 59 of relay 45 is not closed at this time.

The electro-polarized relay 43 has current flowing through both its windings at this time, but the relay is not operated on account 40 of the fact that the current is flowing around in opposite directions in the two windings.

The distant operator now connects her calling device in operative relation in the distant end of the toll line TL and turns the 45 calling device in accordance with the first digit of the desired number. When the calling device is turned off-normal, the ground connection is removed from conductor 12 and battery is applied in its place in a manner 50 similar to that to be subsequently described in connection with a call going in the opposite direction. Responsive to the placing of battery on conductor 12, relay 47, which is connected to conductor 12 as above pointed out, 55 energizes. At armature 63 relay 47 closes a circuit for relay 48. Relay 48 energizes and closes a locking circuit for itself at armature 66; opens a point in the circuit of relay 42 at armature 65; and at armature 67 places 60 ground on conductor 33, thereby extending a ground connection to conductor 25 to make the toll line TL test busy at the line jacks LJ and LJ'. The ground potential is extended further through an I. D. F. jumper to the 65 cut-off relay 14. Relay 14 energizes and cuts

off the ringing-response relay 15 at armatures 16 and 17, and at armature 18 it places ground on the associated conductor, which is accordingly extended through the I. D. F. to conductor 22 to operate the mechanical busy signals associated with the jacks LJ and LJ'. Relay 42 is not operated at this time owing to the fact that its circuit is open at armature 65 of relay 48.

As a further result of the energization of 75 relay 47, the bridge across conductors 35 and 36 is shifted so that it includes the working contact and armature 59, and armature 64 and working contact instead of the right-hand repeating coil windings, the upper 80 winding of the electro-polarized relay 43, and contacts 62 and back contact 64 of relays 46 and 47.

As the distant calling device restores to 85 normal, the circuit through which battery is supplied to conductor 11 is broken a number of times depending upon the digit for which the calling device is operated. Each time the circuit is broken, relay 45 falls back and opens the bridge across conductors 35 90 and 36 at armature 59. Relay 45 also opens the circuit of slow-acting relay 46 at armature 58, but relay 46 remains operated throughout the series of deenergizations of 95 relay 45 due to its slow-acting characteristic. 100

When the distant calling device again reaches its normal position, the toll line conductor 12 is shifted back to ground again, whereupon relay 47 deenergizes and opens the initial energizing circuit of relay 48 at 105 armature 63. Relay 48, however, remains energized through its locking circuit which includes armature 66. Relay 47 also shifts the bridge across conductors 35 and 36 back to the path originally traced. 110

When the distant calling device is again turned, relay 47 responds again to condition the circuits outgoing from the repeater R for repeating impulses. In this manner, all the digits of the desired number are transmitted 115 and the connection is extended to the desired line in the usual manner.

When the called subscriber responds, the current flow in conductors 35 and 36 is reversed at the back bridge relay of the connector with the result that the electro-polarized relay 43 responds and at armature 56 disconnects conductor 12 from ground through relay 47 and connects it instead to battery through the resistance 49. This operation results in the extinguishing of the supervisory lamp at the distant cord circuit in a manner similar to that to be subsequently described in connection with a call in the opposite direction. 120

Assuming that the called subscriber replaces his receiver first when the conversation is terminated, the electro-polarized relay 43 responds and shifts conductor 12 back to ground again through relay 47 with the 125 130

result that supervisory lamp on the distant end of the toll line TL is lighted again.

When the distant operator pulls down the connection, battery is removed from conductor 11 with the result that relay 45 falls back and opens the circuit of relay 46 at armature 58. Relay 46 falls back and opens the bridge across conductors 35 and 36 at armatures 60 and 62, and removes ground from conductor 34 at armature 61. Relay 48 now falls back and removes ground from conductor 33 whereupon the idle condition is restored at the sleeves of the jacks LJ and LJ', and relay 14 falls back and places relay 15 across the toll line again in series with the condenser 19. Responsive to the opening of the bridge across conductors 35 and 36 at armatures 60 and 62 of relay 46, the automatic switches are released in the usual manner.

Assuming now that the distant operator desires the local operator at the near automatic exchange to complete and supervise the connection, the distant operator plugs in with the result that the lineswitch associated with the repeater R, Fig. 1, operates in the hereinbefore described manner to extend the connection to an idle selector.

The distant operator now throws the usual ringing key associated with her cord circuit with the result that ringing current is projected out over the toll line TL and operates the ring-up relay 15. When relay 15 operates its armature proper is locked in its operated position mechanically until the armature of cut-off relay 14 operates. At armature 21, relay 15 closes a circuit for the mechanical busy signals associated with the jacks LJ and LJ', and it closes a circuit through the resting contact and armature 65 for cut-off relay 42 in the repeater R. Relay 42 operates and disconnects the upper winding of relay 43 from around the right-hand talking condenser at armature 52; disconnects conductor 12 from relay 47 at armature 54 and connects it instead to relay 44; and at armature 55 disconnects conductor 11 from relay 45 and connects it to battery through the resistance 59. This latter operation results in the deenergization of relay 45, with the consequent deenergization of relay 46.

As a further result of the energization of relay 15, a circuit is closed at armature 20 for the answering lamp at the answering jack AJ, which circuit includes a jumper on the I. D. F. and the conductor 24.

When the operator notes the lighted condition of the answering lamp at the answering lamp AJ, she inserts the plug of an idle cord circuit into the jack AJ, thereby applying ground to the sleeve of the jack. This ground potential places a busy test on the sleeves of the multiple jacks LJ and LJ'. Also a circuit is closed for the cut-off relay 14. Upon the energization of relay 14, the

armature proper of the relay 15 is unlocked and is allowed to assume its normal position. The circuit of the answering lamp is opened at armature 20, and the initial circuit for relay 42 and for the mechanical busy signals is opened at armature 21, but this circuit is maintained closed at armature 18 of relay 14. At armatures 16 and 17 relay 14 removes the bridge including relay 15 and the condenser 19 from across the conductors 11 and 12.

The answering operator now converses with the calling operator and she extends the connection to the desired line in the usual manner. The former operator has supervision over the called subscriber and when he has hung up his receiver she momentarily throws her ringing key to project generator back over the toll line TL. This operates the usual ring-up supervisory relay in the calling cord circuit to give the calling operator a disconnect signal.

Assuming now that the operator at position No. 2, Fig. 1, receives a call for a subscriber whose line terminates in the distant exchange reached by way of the toll line TL, the operator inserts a plug into the jack LJ', thereby preparing a circuit for the associated supervisory lamp. The ground potential placed on the sleeve of the jack LJ' results in the operation of the cut-off relay 14. At armature 18 relay 14 closes the supervisory circuit with the result that the mechanical busy signals are operated and the multiple circuit is closed for relay 42. At armature 53 relay 42 closes a circuit through armature 57 and its resting contact and contacts on the jack LJ' for the associated supervisory lamp. At armatures 54 and 55 relay 42 shifts conductors 11 and 12 from relays 45 and 47 to battery through resistance 49 and to relay 44. The placing of battery on conductor 11 through the resistance 49 results in the operation of the lineswitch on the distant end of the toll line TL to extend the connection to a first selector.

The calling operator may now operate her ringing key and signal the operator on the distant end of the toll line with results similar to those above pointed out, or she may take further steps to set up the connection automatically independent of the cooperation of the distant operator. Assuming that she decides to take the latter course, the operator inserts the plug P of the dial cord shown in Fig. 2 into the dial jack DJ'. This operation does not produce any immediate results.

When the operator turns the calling device CD off-normal for the first digit in the desired number, a circuit is closed by the off-normal springs of the calling device for relay 101. A multiple circuit is closed through the sleeve of the plug P and through the sleeve of the dial jack DJ' for cut-off relay 41. Relay 41 energizes and disconnects conductors 28 and 30 from the left-hand repeating

coil windings at armatures 50 and 51. As a result of the energization of relay 101 of the dial cord, battery through the impulse springs of the calling device CD and through armature 102 is placed on the tip of the plug P. This circuit replaces the battery supply circuit formerly closed through armature 50 of relay 41. At armature 103 relay 101 places battery through the ring contact of the plug P and through the ring contact of the associated jack on conductor 12 with the result that the distant circuits are prepared for operation in a manner similar to that described hereinbefore. The impulses are transmitted at the impulse springs of the calling device CD in the usual manner upon the return of the calling device to normal. It will be noted that the circuits of relays 101 and 41 are opened simultaneously at the springs of the calling device CD. Relay 101 however is slow acting and it remains operated for a slight interval after relay 41 has restored so that the holding circuit including resistance 49 is reestablished prior to the opening of the circuit through the impulse springs of the calling device.

After the connection has been set up to the called line, the called subscriber responds with the result that battery is placed on the distant end of conductor 12. This results in the energization of relay 44 through armature 54 and its working contact. At armature 57 relay 44 opens the circuit of the supervisory lamp associated with the line jack LJ'.

Assuming that the called subscriber replaces his receiver prior to the pulling down of the connection by the calling operator, battery is removed at the distant end from conductor 12 with the result that relay 44 falls back and relights the supervisory lamp at armature 57.

When the calling operator gets the disconnect signals from both subscribers, she pulls down the connection.

When the plug is removed from the jack LJ', relay 14 falls back and opens the circuit of relay 42. Relay 42 falls back and shifts the circuit to the position shown in the drawing with the result that battery is removed from conductor 11. The connection through the automatic switches in the distant office is released in the usual manner responsive to the removal of battery from conductor 11.

Regarding the plug P, this plug may be left in the dial jack DJ' indefinitely or it may be removed and used to operate another train of switches in case another call comes in before the last one is cleared out. From this it may be seen that there is only one dial cord needed at a position and that it is used to switch the calling device into operative relation with any desired toll line.

What is claimed is:

1. In a telephone system, a two way toll line, automatic switching mechanism for extending connections from said toll line at either end, a sender at one end of said toll line for controlling the switches at the other end, said last mentioned switches and said sender being adapted for different systems of control, a repeater at said other end of said toll line between the toll line and the associated switches for generating impulses of the type to cause the operation of the latter switches, a sender at said other end of the toll line for controlling the switches at said one end of the toll line, and means for connecting said sender directly to the toll line on the toll line side of said repeater. 70 80

2. In a telephone system, a two way toll line, automatic switching mechanism for extending connections from said toll line at either end, a sender at one end of said toll line for controlling the switches at the other end, a repeater at said other end of said toll line between the toll line and the associated switches for repeating impulses to the latter, a sender at said other end of the toll line for controlling the switches at said one end of the toll line, and means including a manual plug and a spring jack for connecting said sender to said toll line on the toll line side of said repeater. 85 95

3. In a telephone system, a multi-position manual switchboard, a trunk line extending therefrom and accessible at each position, supervisory lamps individual to said trunk line, there being a separate lamp at each position, contacts individual to said trunk line at each position for connecting up the supervisory lamp at the calling position only, and means for completing the connection to the lamp upon the termination of the call by the called party. 100 105

4. In a telephone system, a multi-position manual switchboard, spring jacks at each position, an outgoing trunk line connected to one of said spring jacks at each position, means including a manual plug at each position for making connection with the spring jack at the corresponding position, a supervisory lamp individual to said trunk line at each position, and contacts on said jacks whereby the supervisory lamp at the calling position only is connected up. 110 115

5. In a telephone system, a trunk line, a supervisory signal at the outgoing end of said trunk line controlled over one conductor only of said trunk line, a switch control circuit completed over the other conductor only of said trunk line, automatic switches operated according to the system of control utilizing both conductors in series, supervisory means for reversing the current flow in the control conductors of said switches, and means responsive to the operation of said supervisory means for operating said supervisory signal 120 125 130

over the first named conductor of said trunk line.

6. In a telephone system, a two-way trunk line, means at one end thereof for seizing said trunk line and for establishing a control circuit thereover, means for associating a calling device with said trunk line at the other end thereof, and means responsive to the turning of said calling device off normal for preventing the establishment of said first named control circuit and for completing a different control circuit including the sending contacts of said calling device.

7. In a telephone system, a two-way trunk line, means at one end thereof for seizing said trunk line and for establishing a control circuit thereover, means for associating a calling device with said trunk line at the other end thereof, a cut-off relay associated with said trunk line, means responsive to said calling device being turned off-normal for closing a different control circuit over said trunk line through the sending contacts of said calling device and for operating said cut-off relay to prevent the establishment of the first named control circuit.

8. In a telephone system, a two-way trunk line terminating in an automatic switch at each end, the switch at one end being operable over the two conductors, each conductor in a separate circuit, and the switch at the other end being operable over the two conductors of a line in series, means at each end for controlling the switch at the other end, and means at one end for translating the control from the other end into the proper control for the switch at that end.

9. In a telephone system, a two-way trunk line terminating in a repeater at one end, an automatic switch terminating said trunk line at the other end, a jack directly connected to the first mentioned end of the trunk line, means for associating a calling device with said jack, and means effective when the device is turned off normal to disconnect said trunk line from the repeater and to connect it to the sending contacts of the calling device.

10. In a telephone system, a two-way trunk line, a jack and a repeater directly connected to said trunk line at one end thereof, an automatic switch at each end of the trunk line, means for associating a calling device with said trunk line by way of said jack to control the switch at the other end, and means controlled by the calling device to disconnect the repeater from the trunk line.

11. In a telephone system, a trunk line, a switch control circuit and a switch setting circuit each utilizing one conductor of the trunk line and a separate return, means responsive to the initiation of a call for closing said control circuit, means for producing momentary interruptions in said control circuit, means for closing said setting circuit during the interruption of said control circuit,

circuit, automatic switches operated according to the system utilizing both sides of the line in series for setting the switches, and an automatic repeater for translating the control from the trunk line into the proper control to operate said switches.

12. In a telephone system, an incoming trunk, and an outgoing trunk, means for extending a call, over said incoming trunk, means responsive when a call is extended for closing an impulsing circuit including one conductor of said incoming trunk and a separate return, means for producing a series of momentary interruptions in said impulsing circuit, means for closing a control circuit including another conductor of said incoming trunk and a separate return during the series of interruptions in said impulsing circuit, means responsive to the closure of said impulsing circuit for closing a second impulsing circuit including two conductors of said outgoing trunk in series, and means responsive to the closure of said control circuit for placing said second impulsing circuit under the control of said first impulsing circuit.

13. In a telephone system, a first trunk having two branches at the outgoing end, a repeater terminating one branch, a second trunk outgoing from the repeater, means for operating the repeater over only one conductor of said first trunk to extend a loop control circuit over said second trunk, a relay terminating the other branch of said first trunk, a signal, means for operating said relay over two conductors of said first trunk in series, and means responsive to the operation of said relay for actuating said signal and for disabling said loop control circuit.

14. In a telephone system, a trunk having two branches at the outgoing end, an impulse repeater terminating one of said branches, a relay terminating the other of said branches, a calling device associated with the incoming end of said trunk, means for applying a characteristic current to the incoming end of said trunk, means responsive to the calling device being turned off normal for rendering said repeater effective for repeating impulses and for disconnecting said relay from the trunk, and means responsive to the application of said characteristic current to the trunk for operating said relay and for disabling said repeater.

15. In a multi-office telephone system, a trunk line comprising two conductors extending from a manual switchboard in one exchange to an automatic switch in another exchange, a calling device at the switchboard, means for associating said calling device with the trunk line, and means responsive to the off-normal movement of said calling device for establishing a current flow over one conductor of the trunk line to render said switch controllable over the other conductor of the trunk line.

16. In a multi-office telephone system, a trunk line comprising a plurality of conductors extending from a manual switchboard in one exchange to an automatic switch in another exchange, a calling device at the switchboard, means for associating said calling device with the trunk line, means responsive to the off-normal movement of said calling device for establishing a current flow over one conductor of the trunk line, and means in said switch responsive to said current flow for preparing said switch to respond to directive impulses transmitted over another conductor of said trunk line. 70
17. In a multi-office telephone system, a trunk line comprising two conductors extending from a manual switchboard in one exchange to an automatic switch in another exchange, a calling device at the switchboard, means for associating said calling device with the trunk line, and means responsive to the off-normal movement of said calling device for establishing a current flow over one conductor of the trunk line to prepare said switch for operation and for connecting said calling device to the other conductor of the trunk line. 80
18. In a multi-office telephone system, a trunk line comprising a plurality of conductors extending from a manual switchboard in one exchange to an automatic switch in another exchange, a calling device comprising impulsive contacts and off-normal contacts at said switchboard, means for associating said calling device with the trunk line, a normally open switch preparing circuit including one conductor of the trunk line, a normally open switch operating circuit including another conductor of the trunk line and said impulsive contacts, and means responsive to the operation of the off-normal contacts of said calling device for closing both of said circuits. 85
19. In a multi-office telephone system, a trunk line comprising a plurality of conductors extending from a manual switchboard in one exchange to an automatic switch in another exchange, a calling device comprising impulsive contacts and off-normal contacts, means for associating said calling device with the trunk line, a preparing circuit for said switch including one conductor of the trunk line, a control circuit for said switch including a different conductor of the trunk line and means responsive to the closure of the off-normal contacts of the calling device preparatory to the operation thereof for connecting a source of current to said preparing circuit and for connecting said impulsive contacts to said control circuit. 105
20. In a telephone system, a combined manual and automatic trunk line connecting two exchanges, a plurality of branches of the trunk line at one exchange, a manual answering jack terminating the first branch, a man- 120
- ual calling jack terminating the second branch, a dialling jack terminating the third branch, and an automatic switch terminating the fourth branch. 125
21. In a telephone system, a combined manual and automatic trunk line connecting two exchanges, a plurality of branches of the trunk line at one exchange, a manual answering jack terminating one branch, a manual calling jack terminating another branch, an automatic switch terminating another branch, a dialling jack terminating another branch, and means controlled from said dialling jack for disconnecting said other branches from the trunk line. 130
22. In a telephone system, a trunk line terminating on one side of a distributing frame, a calling multiple for the trunk terminating on the same side of the frame, an answering multiple for the trunk also terminating on the same side of the frame, a line relay circuit terminating on the other side of the frame, and jumpers operatively connecting said trunk line with said multiples and said circuit. 135
23. In a telephone system, a trunk line terminating on one side of a distributing frame, a calling multiple for the trunk terminating on said one side of the frame, an answering multiple for the trunk also terminating on said one side of the frame, a line relay circuit terminating on the other side of the frame, a local trunk extending to an impulse repeater terminating on said other side of the frame, and jumpers operatively connecting said trunk line with said multiples, said circuit and said local trunk. 140
24. In a telephone system, a trunk line terminating on one side of a distributing frame, answering and calling multiples terminating on the same side of the frame, an impulse repeater having incoming and outgoing conductors terminating on the other side of said frame, jumpers connecting the trunk line with the incoming conductors of said repeater, and jumpers connecting the outgoing conductors of said repeater with said multiples. 145
- In witness whereof, I hereunto subscribe my name this 24th day of September, A. D. 1925. 150
- JOHN WICKS. 155
